(57) **CLAIM**

The ornamental design for a display panel, as shown and described.

DESCRIPTION

FIG. 1 is a left front perspective view of a display panel showing our new design, with the right front perspective view being a mirror image thereof; and,

FIG. 2 is a front elevation view thereof.

Views not depicted form no part of the claimed invention. The dashed-dot-dashed lines define the boundary of the claimed design. The broken lines of even length depict graphics on the display screen that are not part of the claimed design.
